CLAIM

The ornamental design for a cord dispenser for video display and associated camera, as shown and described.

DESCRIPTION

FIG. 1 is a front and side perspective view of a cord dispenser for video display and associated camera showing our new design;

FIG. 2 is a rear and side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof;

FIG. 8 is a top plan view thereof;

FIG. 9 is a front and side perspective view showing the cord dispenser for video display and associated camera in an exemplary environment attached to a rear of a display housing and pivoted relative thereto; and,
FIG. 10 is a bottom plan view showing the cord dispenser for video display and associated camera in an exemplary environment attached to a rear of a display housing.

The broken lines shown in FIGS. 1-10, showing a rear portion of a display housing, a camera, a cable, an adapter and other features, are for illustrative purposes only and form no part of the claimed design.
